CLAIM

I claim the ornamental design for the light emitting diode, as shown and described.

DESCRIPTION

FIG. 1 is a rear elevational view of the light emitting diode showing my new design;

FIG. 2 is a left side elevational view thereof;

FIG. 3 is a top plan view thereof;

FIG. 4 is a right side elevational view thereof;

FIG. 5 is a front elevational view thereof;

FIG. 6 is a bottom plan view thereof; and,

FIG. 7 is a perspective view thereof.
